[57] CLAIM

The ornamental design for a vial protective tray, as shown and described.

DESCRIPTION

FIG. 1 is a front elevational view of a vial protective tray showing our new design; the rear elevational view being a mirror image thereof;

FIG. 2 is a top plan view thereof;

FIG. 3 is a left side elevational view thereof;

FIG. 4 is a right side elevational view thereof;

FIG. 5 is a sectional elevational view thereof taken along line 5—5 of FIG. 2;

FIG. 6 is a sectional elevational view thereof taken along line 6—6 of FIG. 2; and,

FIG. 7 is a bottom plan view thereof.

Fig.2. ← 6*Fig.1. ← 6**Fig.3.**Fig.4.**Fig.5.**Fig.6.**Fig. 7.*
